APPARATUS FOR FILLING CUSHIONS AND
LIKE ARTICLES

Robert W. Stavely, Cleveland Heights, Ohio

Application May 23, 1941, Serial No. 394,825

2 Claims. (Cl. 226—43)

This invention relates to apparatus for use in filling cushions with feathers, down, and other materials which, on account of their light weight and finely divided condition, are liable to escape into the room in which the filling operation is performed, thereby to produce irritation of the eyes and respiratory organs of the parties in the vicinity where the filling operation is conducted, as well as to create a dangerous fire hazard which necessitates the adoption of expensive preventive measures.

It is the general purpose and object of my invention to provide an apparatus whereby the escape of the materials used in filling cushions and like objects will be eliminated and also whereby the time consumed in the filling operation may be greatly reduced as compared with that required where other apparatus for like purposes are employed and with which I am familiar.

I accomplish the foregoing objects in and through the construction and arrangement of parts shown in the drawings forming part hereof wherein Fig. 1 represents an elevation of an apparatus constructed in accordance with my invention; Fig. 2 a similar view taken at right angles to Fig. 1, the filling bag, cushion and sleeve being omitted; and Fig. 3 an enlarged detail taken on the line 3—3 of Fig. 2 and looking in the direction of the arrows, showing the sleeve, filling bag and part of the cushion case.

Describing by reference characters the various parts illustrated herein, 10 denotes a casing, preferably of metal, and generally T-shaped. 11 denotes a vertical supporting member, the lower end of which is formed into a yoke, the opposite arms 11^a of which are shown as secured to opposite sides of the vertical branch 10^a of the casing, as by bolts 11^b. The lower ends of the arms are connected by an integral brace 11^c, and secured to the central portion of the said brace, as by welding or brazing, is the upper arm or branch 12 of a U-shaped bracket, the said arm being connected by a vertical branch 12^a with a lower branch 12^b. The end of the arm or branch 12 which is remote from the connecting portion 12^a is bent upwardly, as shown at 12^c, thereby to engage the bottom of the casing 10. The upper arm or branch 12 cooperates with a screw clamp 13 to secure the casing 10 and the supporting member to a table or other support 14. The said clamp comprises a stem 13^a which is threaded through the lower arm or branch 12^b, being provided at its upper end with a bearing plate 13^b adapted to be brought into engagement with the lower sur-

face of a support 14, the lower end of the clamp being provided with an operating handle 13^c.

15 denotes an arm which is provided with a sleeve 15^a whereby it is slidably mounted upon the vertical supporting member 11, the width of the opening in the sleeve being slightly greater than the width of the member 11 whereby the arm 15 may remain in any position to which it may be adjusted upon the member 11 by the slight tilting action imparted to said arm by the container for the filling material supported thereby.

16 denotes the bag or container for the material employed in filling the cases of cushions and the like. The seam closing the bottom of the container is ripped a sufficient distance to provide an opening which is fitted snugly about the flange at the top of the vertical branch of the casing 10 and the bag or container itself is suspended from the arm 15 by any suitable support, 20 a spring clip 15^b having its upper end secured to the arm being here shown as employed for this purpose.

17 denotes the case of the cushion or similar article which is to be filled from material contained in the bag or receptacle 16. This case is of the usual construction, being provided with one or more longitudinal partitions 17^a, which tend to prevent the filling material from shifting in the completed cushion, and is applied to and around a flange 10^c at one end of the horizontal portion of the casing 10 in the same manner that the lower end of the bag or receptacle 16 is applied to the upper end of the vertical branch 10^a of the casing. This flange is shown as serrated at the top and bottom thereof, as indicated at 10^d, which serves to prevent the case 17 from rotating with respect to the casing 10.

18 denotes a sleeve, preferably of cloth, one end of which is provided with an elastic 18^a whereby said end may be snugly fitted around a flange 10^c at the opposite end of the casing 10. The opposite end of the sleeve is also provided with an elastic 18^b, the opening being of such size, when the elastic is expanded, that the hand and forearm of the operator may be inserted into the sleeve, the elastic causing the outer end of the sleeve to form a close grip about the operator's arm.

A simple, inexpensive and convenient means for insuring a close fit of the receiving end of the cushion case about the flange 10^c is by the use of a spring clip 19, similar to the spring clip 15^b, and the opposed jaws of which grip therebetween the receiving end portion of the cushion case as closely as possible to said flange. The bottom of the bag or receptacle 16 may also be tightly fitted

about the flange 10^b by the use of a similar clip 20, which is clipped onto the bottom of the bag as closely as possible to the said flange. These clips serve to restrict the openings in the receiving end of the case 17 and the bottom of the bag or receptacle 16 to an extent that will prevent the escape of any of the filling material.

With the parts arranged as described, the operator inserts his hand and forearm as far as may be necessary within the sleeve 18, grasps the material that may be in the casing 10 or in the receptacle thereabove and packs the same within the casing 17. As the material within the container 16 may be packed so tightly as not to descend readily into the casing 10, he is enabled to reach his hand upwardly, as far as may be necessary, into the said bag or container, take a handful of the material therein and pack the same in proper position in the case 17, repeating the operation of grasping the material and packing it within the case until the latter shall have been evenly and sufficiently filled.

For the purpose of preventing any material within the case 17 from being withdrawn into the casing 10, due to the withdrawal of the hand of the operator, a flap valve 21, preferably of rubber, is secured to the branch 10^a of the casing, the said flap valve normally extending downwardly into engagement with the bottom of the casing and presenting a concave surface toward the body of the casing. This flap valve normally closes communication between the body of the casing 10 and the neck portion of the same which is provided with the flange 10^c. Due to its resiliency, because made of material such as rubber, the lower portion will be swung into the neck to which the case 17 is secured when the hand of the operator is inserted into the said case, but will fit more or less snugly about the wrist and arm of the operator as his hand is inserted further into the said case. When the operator is withdrawing his arm, wrist and hand from the case 17, the valve performs a sealing function about these parts and, due to this action and

to its shape and lateral extent, it snaps into closed position as soon as the hand is disengaged from the same, and thereby prevents the material within the case from being drawn into the body of the casing 10.

With an apparatus such as shown and described herein, it is possible for an operator to fill the cases for cushions with greater rapidity than can be accomplished by any other apparatus for this purpose with which I am acquainted, and to perform this operation without liability of the filling material escaping into the room or space surrounding the apparatus.

Having thus described my invention, what I claim is:

1. An apparatus for the purpose specified comprising a generally T-shaped casing having opposed branches and an intermediate branch, means for forming a tight connection between an outlet in a container and the intermediate branch, means for securing a receiving case to one of the opposed branches with the receiving opening of the said case in close engagement with the said branch, a sleeve secured to the other of the opposed branches of the casing and adapted to fit snugly about the arm of an operator, and a resilient flap valve secured to and located within said casing adjacent to the inner end of the branch of the casing to which the case is attached, the said valve adapted to yieldably engage the arm, wrist and hand of the operator while being inserted into and removed from the receiving case and normally closing communication between the body of the casing and the said branch.

2. In the apparatus set forth in claim 1, vertically adjustable means engageable with the closed end portions of containers, the outlets whereof are secured to said intermediate branch of the T-shaped casing whereby the said containers may be supported in a position to facilitate the discharge of the entire contents thereof into the said intermediate branch.

ROBERT W. STAVELY.
